(57) **CLAIM**

The ornamental design for a water container, as shown and described.

DESCRIPTION

The present application is related to commonly assigned U.S. patent application Ser. No. 29/529,530 filed Jun. 8. FIG. 1 is a top front perspective view of a water container showing our new design;

FIG. 2 is a bottom view thereof;

FIG. 3 is a front view thereof;

FIG. 4 is a rear view thereof;

FIG. 5 is a right side view thereof;

FIG. 6 is a left side view thereof; and,

FIG. 7 is a top view thereof.

The broken lines in the drawing depict portions of the water container that form no part of the claimed design.

The present application is for the ornamental design of water container having, among other things, an integrated handle. While not part of the design, the water container normally includes a logo or image positioned on one or more faces of the container.
